UNITED STATES PATENT OFFICE.

ARTHUR M. McPHILLIPS, OF BELOIT, WISCONSIN.

BEATER-ENGINE ROLL.

REISSUED

Application filed November 1, 1927. Serial No. 230,281.

This invention relates to beating engines for macerating paper stock and has special reference to the beater bar or knife, the object being to provide a beater bar by the use of which a more complete circulation and disintegration of the stock than has heretofore been possible will be attained. The invention is illustrated in the accompanying drawing and will be hereinafter 10 fully described, the novel features being particularly pointed out in the appended claims.

In the drawing, Figure 1 is a plan view of a beater roll having the present invention embodied therein;

15 Figure 2 is an end view of a portion of the roll;

Figure 3 is a view showing two of the bars in elevation.

The beater roll is mounted in the tank or 20 tub in the usual or any approved manner and consists of disks, one of which is indicated at 1, secured upon a central shaft 2, beater bars or knives 3 extending parallel with the shaft and held to the disks by end 25 rings 4, and wedge blocks 5 driven between adjacent knives or bars to maintain them in fixed spaced relation. Generally the bars or knives 3 have their inner edges seated in recesses provided therefor in the edges of 30 the several disks, and the end rings engage in notches 6 in the ends of the knives so that when the several parts are assembled the knives will be very firmly secured. In the outer edge of each knife or bar, spaced 35 notches or recesses 7 are formed and the bars are arranged so that the notches in adjacent bars are staggered, each notch in each bar being alined circumferentially of the roll with a lug or tooth 8 between two notches in 40 the adjacent bars. It will be noted, more particularly upon reference to Figure 3, that the opposite outer corners of alternate bars are cut away, as at 9, on lines corresponding to the contours of the notches 7, 45 so that the staggered notch structure is car-

ried to the extreme ends of the beater roll. The beater roll is rotated in the tank in the usual manner to cause the bars to successively impinge upon and work through the stock. The notches in the working edges 50 of the bars act upon the stock so as to quickly disintegrate the same, the stock being torn or shredded and the tendency of the same to wrap around the roll being overcome. The bar embodying this invention creates a greatly increased suction through the stock so that the latter circulates more rapidly and efficiently than with the devices now in use and the work is completed in less time and with less power than has heretofore been 55 necessary.

While, for illustrative purposes, the invention has been shown embodied in singly spaced bars, the bars may be arranged in clusters, and it will be understood that the 60 dimensions of the notches may be varied according to the characteristics of the stock to be treated. In practice, a plurality of interchangeable sets of bars will be provided so that, before starting work, the operator 65 may apply to the roll the bars best adapted to the particular stock which is to be treated.

Having fully described my invention what I claim as new and desire to secure by Letters-Patent, is:—

1. A beater roll having circumferentially spaced beater knives provided with spaced notches in their working edges, the notches in adjacent knives being relatively staggered. 70

2. A beater roll having circumferentially spaced beater knives, the opposite outer corners of alternate knives being cut away and the knives having spaced notches in their working edges, the notches in adjacent 75 knives being relatively staggered.

In testimony whereof, I have signed this specification.

ARTHUR M. McPHILLIPS.
